a⁴ Inventor:
Mordecai Bassan,
By his Attorney, Geo. W. Misch

UNITED STATES PATENT OFFICE.

MORDECAI BASSAN, OF BROOKLYN, NEW YORK.

AUTOMATIC TOY.

Application filed April 30, 1923. Serial No. 635,476.

To all whom it may concern:

Be it known that I, MORDECAI BASSAN, a native of Palestine, having declared my intentions of becoming a citizen of the United States, and being a resident of the borough of Brooklyn, county of Kings, city and State of New York, have invented certain new and useful Improvements in Automatic Toys, of which the following is a specification sufficient to enable others conversant with the art to which the invention appertains to utilize the same in a practical manner.

The object of my invention is the production of a novel and interesting toy in which is simulated automatically, upon the release of suitable mechanism, the ringing of a bell, the opening of a door, the presence on the exterior of a figure before the open door way, and the visual appearance of one or more figures located within an enclosure representing externally a house or other place of abode or shelter, all as hereinafter fully set forth,—the invention consisting in the specific construction, arrangement and combination of parts and appurtenances described and claimed.

In the accompanying drawings I exemplify a practical embodiment of the essential features of my invention, although I do not limit myself to the identical form and construction of parts shown, since modifications may be made in minor details and equivalent mechanical expedients resorted to with like results, and without departing from the spirit and intent of my invention in this respect.

With this understanding,

Fig. 1, represents an exterior front elevation of my toy compartment with the door closed, as when the operative parts are held set in retracted normal position;

Fig. 2, is a like view of the front of the toy compartment after the automatic mechanism has been released and completed its advance function;

Fig. 3, is a horizontal section taken upon plane of line 3—3, Fig. 4, showing the operative parts in normal retracted position;

Fig. 4, is a vertical section taken upon plane of line 4—4, Fig. 3;

Fig. 5, is a rear exterior elevation of the compartment, the setting or retractile rod being shown in cross section, with the knob omitted;

Fig. 6, is a view like unto Fig. 3, showing the operative parts in advanced position;

Fig. 7, is a detail view of the bell and actuating means on line 7—7 of Fig. 4;

Fig. 8, is a detail view of the outer portion of the slotted lever which controls the spring power spindle;

Fig. 9, is a section taken upon plane of line 9—9, Fig. 8;

Fig. 10, is a detail view of the retractile setting rod;

Fig. 11, is a detail view showing the engagement of the latch therewith;

Fig. 12, is diagrammatic representation of one of the movably mounted figures, made with a vibratory head;

Fig. 13, is a view thereof taken at right angles to Fig. 12;

Fig. 14, is a horizontal section taken upon plane of line 3—3, Fig. 4, showing a modification.

Fig. 15, is a partial front elevation similar to Fig. 2, illustrating the result of the modification shown in Fig. 14.

A, represents in simplest box form, and symbolically, a house, compartment, or enclosure of any desired shape or configuration, in which the main parts of the automatic mechanism are installed; the front wall *a* of said compartment A, being provided with windows *w*, *w'*, and a door *d*, hinged to open inward.

S, is a rotative spindle, the end trunnions of which are mounted in bearings formed for the purpose in the top *a'*, and bottom *a''*, of the box or compartment A. A coiled spring *s*, encircles the upper portion of this rotative spindle *S*, being secured at one end *s'*, to the top *a'*, of the compartment A, and at its other extremity *s''*, to said spindle *S*, as indicated more particularly in Fig. 4, of the drawings. This spring *s*, tends constantly to rotate the spindle *S*, in the direction of the arrows, Figs. 3, 4 and 6, of the drawings. This tendency to rotation is controlled however, through the medium of the lever arm *s³*, rigidly attached to and extending radially from said spindle *S*, and pivotally connected with the retractile setter rod *R*,—this pivotal connection being slidable as related to the lever arm *s³*, and preferably effected by means of a pin *r*, on the inner end of the rod *R*, engaging with a longitudinal slot *s³'*, in said lever arm *s³*, although any equivalent mechanical expedient may be

100

105

110

resorted to for effecting the slidable connection between the lever arm s^3 , and the retractor rod R .

The retractile setter rod R , extends 5 through the rear wall a^3 , of the compartment A, its outer extremity being formed with a knob or handle r' , for convenience of manipulation, and its medial portion being formed with a recess r^2 , for engagement with 10 one end l , of a latch lever L, pivotally supported at l' , to the rear wall a^3 , of the compartment A, and is formed at its other extremity with a protuberant handle r^2 . By 15 means of this latch L, the rod R, and other operative parts may be locked in retracted position against the resistance of the coiled spring s , on the rotative spindle S. A retractile spring l^2 , tends constantly to hold the latch L, in engagement with the groove 20 r^2 , of the rod R, so that when said rod is retracted the parts will lock automatically.

A figure-supporting arm s^4 , extends rigidly and radially from the lower portion of 25 the rotative spindle S, and protrudes through a horizontal slot a^4 , in the front wall a , and side wall a^4 , of the compartment A, as shown more particularly in Figs. 1, 2, and 4, of the drawings. On the outer portion of this supporting or carrier arm s^4 , is 30 mounted a figure f , of any desired character, as for instance the figure of a person presumably seeking entrance to the apartment A, the portion of the carrier arm s^4 , within the enclosure having mounted upon it a second figure f' , presumably representing a person in attendance at the door d .

Another radial arm s^5 , also rigidly attached to the rotative spindle S, extends 35 from the side thereof opposite, substantially, to that of the lever arm s^3 , as shown more particularly in Figs. 3, 4, and 6, of the drawings, and has articulately attached to it a link d' , articulately connected in turn with the inner side of the door d , as shown more particularly in Figs. 3, and 6, of the drawings.

B, is a bell which is rung indirectly by means of the spring s , on the rotative spindle S, when the rod R, is released from the latch L. That is to say, the rounded outer 50 cam end s^x , of the lever arm s^3 , normally in contact with the roller c , on the hammer arm C, as when the parts are retracted immediately at the inception of the advance of said lever arm a^3 , under the impulse of the spring 55 S, rocks the said hammer arm C, on its pivotal support c , against the resistance of the retractile spring c^2 , causing the hammer head c^3 , to strike the periphery of the bell B, thereby vibrating the latter and sounding 60 an announcement. As soon as the cam-shaped end s^x , of the lever arm s^3 , clears the roller c , of the hammer rock arm C, the latter is retracted by the spring c^2 , which returns the hammer end of said rock arm C, to 65 contact with the stop c^4 .

In the advance movement of the lever arm s^3 , the rod R, simply follows, its function being only to return the operative parts to normal position against the resistance of the power spring s , after their advancement.

The rotative movement of the spindle S, when thus released by the latch L, and after the ringing of the bell B, as above stated, opens the door d , through the medium of the radial arm s^5 , and link d' , and simultaneously advances the carrier arm s^4 , so as to present the figures f , f' , at the front of the device, the figure f , before the open door way, and the figure f' , therewithin.

In the modification shown in Figs. 14 and 15, an additional figure f^2 , or the representation of a head of any kind, is provided for, the same being mounted on a bracket d^2 , on the rear side of the door d , so that when the operative parts are advanced as above described, a face will be seen through the window w' , as indicated more particularly in Fig. 15, of the drawings.

In fact, any desired plural number of figures or objects may be thus provided for appearance when the operative parts are advanced, and modifications in this respect resorted to with the use of the same mechanism, the distinctive feature of which is the rotative spring power spindle S, for the actuation of appurtenances, substantially as herein set forth.

In the arrangement shown the return of the operative parts to normal position by means of the rod R, will obviously again sound the bell B, at the completion of such retractile movement, but this is rather an advantage than otherwise, as indicating that the operation is complete, and ready for relocking by means of the latch L.

The bell B, may be omitted if desired, without impairing the efficiency of the other operative parts, but is a desirable accessory thereto.

What I claim as my invention and desire to secure by Letters Patent is,

1. In an automatic toy of the character designated, the combination of a compartment, a hinged door, a rotative spindle, a power spring connected therewith, a door actuating arm rigidly protuberant radially therefrom, and a link articulately connecting said door with said arm, a carrier arm rigidly protuberant from said rotative spindle, and slidably through an opening in said compartment, a figure mounted on said carrier arm, a lever arm rigidly attached to said rotative spindle and slidably connected with a retractile rod, substantially in the manner and for the purpose set forth.

2. In an automatic toy of the character designated, the combination of a compartment, a hinged door, a rotative spindle, a power spring connected therewith, a door

- actuating arm rigidly protuberant radially therefrom, and a link articulately connecting said door with said arm, a carrier arm rigidly protuberant from said rotative 45 spindle, and slidably through an opening in said compartment, a figure mounted on said carrier arm, a retractile rod, a lever arm rigidly attached to said rotative spindle and slidably connected 50 with said retractile rod, and a latch engageable with a retaining shoulder on said retractile rod, substantially in the manner and for the purpose set forth. 55
3. In an automatic toy of the character 15 designated, the combination of a compartment, a hinged door, a rotative spindle, a power spring connected therewith, a door actuating arm rigidly protuberant radially therefrom, and a link articulately connecting 20 said door with said arm, a carrier arm rigidly protuberant from said rotative spindle, and slidable through an opening in said compartment, a plurality of figures mounted on said carrier arm, a lever arm rigidly attached 25 to said rotative spindle and slidably connected with a retractile rod, substantially in the manner and for the purpose set forth. 30
4. In an automatic toy of the character 35 designated, the combination of a compartment, a hinged door, a rotative spindle, a power spring connected therewith, a door actuating arm rigidly protuberant radially therefrom, and a link articulately connecting said door with said arm, a carrier arm rigidly protuberant from said rotative spindle, and slidably through an opening in said compartment, a figure mounted on said carrier arm, a lever arm 40 rigidly attached to said rotative spindle and slidably connected with a retractile rod, and a bell actuated by said lever arm, substantially in the manner and for the purpose described. 45
5. In an automatic toy of the character 50 designated, the combination of a compartment, a hinged door, a rotative spindle, a power spring connected therewith, a door actuating arm rigidly protuberant radially 55 therefrom, and a link articulately connecting said door with said arm, a carrier arm rigidly protuberant from said rotative spindle, and slidable through an opening in said compartment, a figure mounted on said carrier arm, a lever arm rigidly attached to said rotative spindle and slidably connected with a retractile rod, and a figure head 60 mounted on a supporting bracket on the rear of the door and observable through a window in the front of said compartment, substantially in the manner and for the purpose set forth. 65
6. In an automatic toy of the character 70 designated, the combination of a compartment, a hinged door, a rotative spindle, a power spring connected therewith, a door actuating arm rigidly protuberant radially 75 therefrom, and a link articulately connecting said door with said arm, a carrier arm rigidly protuberant from said rotative spindle, and slidable through an opening in said compartment, a figure mounted on said carrier arm, a lever arm rigidly attached to said rotative spindle and slidably connected with a retractile rod, and a bell actuated by said lever arm, substantially in the manner and for the purpose described. 80
